UNITED STATES PATENT OFFICE.

JOHN C. TITUS, OF NEW BREMEN, OHIO, ASSIGNOR OF ONE-HALF TO THE NEW BREMEN MACHINE COMPANY, OF SAME PLACE.

BRICK OR TILE MACHINE.

SPECIFICATION forming part of Letters Patent No. 478,267, dated July 5, 1892.

Application filed June 11, 1891. Serial No. 395,893. (No model.)

To all whom it may concern:

Be it known that I, JOHN C. TITUS, of New Bremen, Auglaize county, Ohio, have invented certain new and useful Improvements in Brick or Tile Machines, of which the following is a specification.

This invention pertains to that class of brick or tile machines in which the clay is forced out of a pug-cylinder into a plunger-chamber by means of a feed-wing on the pug-shaft, the clay being forced out of the chamber through a die by the action of a plunger; and the nature of the improvements will be readily understood from the following description, taken in connection with the accompanying drawings, in which—

Figure 1 is a vertical longitudinal section of a machine exemplifying my improvements; Fig. 2, a horizontal section of the same; Fig. 3, a horizontal section of the pug-cylinder, and Fig. 4 an edge view of the feed-wing.

In the drawings, A indicates the usual pug-cylinder; B, the pug-shaft disposed centrally therein and adapted to be rotated by any of the usual means; C, the plunger-chamber underneath the pug-mill and arranged to receive the clay therefrom; D, the opening in the floor of the plug-mill, through which the clay goes from the pug-mill to the plunger-chamber; E, the die forming the end wall to the plunger-chamber and through which it is the duty of the plunger to force the clay to form the tile or brick, the intention being to employ any desired or suitable or usual form of die; F, the feed-wing secured to and carried around by the pug-shaft, this feed-wing having its under surface sloped upwardly and forwardly from near the floor of the pug-cylinder, the length of the feed-wing being in excess of the length of the discharge-opening D; G, the plunger fitted to reciprocate in the plunger-chamber to and from the die and past the opening D, the exemplification showing this plunger as of skeleton box form, with the pug-shaft passing down through it; H, a pressure-cylinder for steam or water or other pressure fluid, this cylinder being shown in the exemplification as arranged tandem to the plunger-chamber; J, the piston of the pressure-cylinder; K, the piston-rod connecting the pressure-piston and the plunger; L, the valve of the pressure-cylinder, (shown as an ordinary slide-

valve,) the arrangement of pressure-cylinder and valve being the same as in ordinary slide-valve steam-engines; M, an eccentric driven by the pug-shaft, the exemplification showing the eccentric as being secured directly to the pug-shaft; N, the eccentric-rod; O, the valve-stem; P, a bell-crank lever pivoted to the plunger-chamber and having one of its arms engaged by the eccentric-rod and the other arm connected with the valve-stem; Q, a segmental flange projecting upwardly from the floor of the pug-mill just inward of the discharge-opening D, this flange forming an inner fence to the discharge-opening, between which fence and the wall of the pug-mill the feed-wing F travels, the arm which attaches the feed-wing to the pug-shaft being disposed high enough to clear the top of this fence; R, an eccentric or volute arm mounted upon the arm of the feed-wing, this eccentric-arm presenting outwardly a wall about opposite the feed-wing and at such distance from the pug-shaft that its extremity will just clear the inner surface of the fence Q; and S, a spur-gear of the pug-shaft, exemplifying ordinary means for use in connection with the driving of the pug-shaft.

As the pug-shaft revolves the feed-wing is carried around in the pug-cylinder near the floor thereof, passing between the cylinder-wall and the fence and over the discharge-opening D, forcing down into the plunger-chamber the clay that is over the opening. The eccentric-arm R forces the clay outwardly from the center and into the path of the feed-wing and forces it into the space behind the fence over the discharge-opening. The clay is free to pass back to the center of the pug-cylinder behind the eccentric-arm, except at the fence, where it is retained till the feed-wing forces it through the discharge-opening. The clay being at liberty to return to the center, except at the fence, relieves the feed-wing of unnecessary vertical strain while passing around to the discharge-opening. Clay behind the fence becomes dammed up by clay in advance of it which has not yet been able to move to the center of the pug-mill, and consequently when the feed-wing attacks the clay behind the fence the clay finds its only free escape through the discharge-opening.

The valve-gear of the pressure-cylinder is

operated directly from the pug-shaft, and consequently the valve must move in unison with the pug-shaft. At each rotation of the pug-shaft the valve is moved and steam admitted behind the piston and the plunger forced forward past the discharge-opening D, the clay being thereby forced out through the die, the pug-shaft continuing to turn, then moving the valve the other way and causing the piston and plunger to retreat and permit the plunger-chamber to receive a new charge of clay from the pug-mill.

I claim as my invention—

1. In a brick or tile machine, the combination, substantially as set forth, of a pug-mill having a discharge-opening in its floor, a fence projecting upwardly from said floor near the inner margin of the discharge-opening, an upwardly and forwardly sloping feed-wing carried by the pug-shaft in a path over the dis-

charge-opening, and a volute or eccentric arm carried by the pug-shaft at the level of the feed-wing.

2. In a brick or tile machine, the combination, substantially as set forth, of a plunger-chamber, a die, a plunger working in the plunger-chamber, a pressure-cylinder having a piston connected with said plunger, a valve for said cylinder, a pug-mill arranged to discharge into said pressure-cylinder and having a pug-shaft, and valve-gearing disconnected from said plunger and connecting said pug-shaft and valve, whereby the valve is positively moved in unison with the revolutions of the pug-shaft.

JOHN C. TITUS.
